UNITED STATES PATENT OFFICE

FRANK A. KUCERA, OF CHICAGO, ILLINOIS, ASSIGNOR TO UNION SPECIAL MACHINE COMPANY, OF CHICAGO, ILLINOIS, A CORPORATION OF ILLINOIS

FABRIC GUIDING MEANS FOR SEWING MACHINES

Application filed February 25, 1932. Serial No. 595,187.

The invention relates to new and useful improvements in a fabric guiding means for forming hem folds, and more particularly to a fabric guiding means wherein the member over which the fabric section is folded may be withdrawn at will for the finishing of certain portions of the seam.

An object of the invention is to provide a simple form of fabric guiding means for infolding the edge portion of the fabric section to form a hem of a predetermined width wherein a fabric supporting and guiding member extending across the stitching line may be manually shifted to withdraw the same from the hem fold and may also be adjusted to different set positions within the hem fold.

A further object of the invention is to provide a fabric guiding means of the above type wherein the support for the fabric guiding and supporting member is adjustable toward and from the stitching line and serves as an edge guide for the infolded portion of the fabric.

A further object of the invention is to provide a fabric guiding means of the above type wherein the fabric supporting and guiding member extending into the hem fold is provided with a stop contacting with the supporting member therefor for limiting the movement of the fabric supporting and guiding member in the direction of movement of the fabric.

In the drawings:—

Figure 1 is a plan view of the fabric guiding means embodying the improvements and a portion of a work support with the parts applied thereto;

Fig. 2 is a sectional view longitudinally through the fabric guiding means and in a direction at right angles to the line of feed;

Fig. 3 is a sectional view on the line 3—3 of Fig. 1;

Fig. 4 is a view in plan showing a portion of the work support, the fabric supporting and guiding member, the support therefor with the fabric supporting and guiding member turned so as to withdraw the same from the hem fold to permit the finishing of the stitching of the hem; and

Fig. 5 is a diagrammatic view showing the hem fold and the position of the same relative to the stitching lines.

The invention is directed to a guiding means for sewing machines which forms a hem fold in a fabric section. The fabric guiding means includes a member located at one side of the stitching line which guides and underfolds the edge portion of the fabric section. Said fabric guiding means also includes a fabric supporting member which is pivotally mounted on a supporting plate and disposed so as to extend within the hem fold and across the stitching line. Both the fabric guiding member for underfolding the edge portion and the fabric supporting and guiding member which cooperates therewith are mounted on the work support for independent adjustments toward and from the line of stitching. The fabric supporting and guiding member is made in sections so that the outer end thereof which cooperates with the guiding member underfolding the edge portion may be shifted relative thereto without changing the position of the supporting plate for said fabric guiding and supporting member. Said fabric supporting and guiding member is also provided with a stop for limiting the inward swinging motion thereof on the supporting plate and for holding said fabric guiding and supporting member normally in a set position.

Referring more in detail to the drawings, the improved fabric guiding means is shown as attached to a flat work support 1 which is provided with a throat plate 2 having openings 3, 3 through which needles 4, 4 pass. The throat plate is also provided with slots 5 in which the feed dog 6 operates to feed the fabric in the direction indicated by the arrow 7 in Fig. 1. Cooperating with the needles 4, 4 beneath the work support is a single thread carrying looper which forms loops which join the needle thread loops. In Fig. 5 of the drawings, a fabric section F is shown, the edge portion of which is underfolded as indicated at f for forming a hem. The left-hand needle 4 forms a line of stitching indicated at n, which line of stitching is disposed outside of the extreme edge of the under-

folded portion *f*. The right-hand needle 4 forms a line of stitching indicated at *n'* which penetrates the body portion of the fabric section and the underfolded edge portion 5 *f*. The looper thread 7 joins these needle loops and covers the edge of the fabric section.

The present fabric guiding means is designed for stitching a hem fold such as shown 10 in Fig. 5. Said fabric guiding means includes a fabric guiding member 8 which is located at one side of the stitching lines, which are the lines of stitches formed by the needles 4, 4. This fabric guiding member 15 8 is secured to the work support by screws 9, 9 passing through a slot 10 which is disposed so that the fabric guiding member 8 may be adjusted to different set positions in a direction at right angles to the line 20 of feed or the stitching lines. The fabric guiding member 8 is provided with a curved guiding member 11 which extends over the throat plate and terminates in front of the needle openings 3, 3. The purpose of this 25 guiding member 8 is to guide and aid in underfolding the edge portion of the fabric section.

Cooperating with this fabric guiding and 30 folding member 8 is a fabric supporting and guiding member 12 which is pivoted at 13 to a supporting plate 14. The supporting plate 14 is provided with a slot 15 through which holding screws 16, 16 are passed and threaded into the work support. This permits the 35 fabric supporting and guiding member to be shifted as a whole in a direction at right angles to the line of feed or the stitching lines toward and from the fabric guiding member 8. The supporting plate 14 is so positioned 40 on the work support that the edge 17 thereof serves as an edge guide for the underneath folded portion of the fabric section. Said supporting plate is set so that the edge of the underfolded portion will be directed between 45 the stitching lines as shown in Fig. 5. This supporting plate 14 has the rear edge thereof tapered downwardly as indicated at 18 so as to permit the body portion of the fabric section to pass down underneath the presser 50 foot.

The fabric supporting and guiding member 12 is formed in two sections. It includes a body portion 12^a in which is mounted a plate 12^b having the outer corners thereof rounded as indicated at 19 and 20. This plate 12^b is the part which extends within the hem fold and across the stitching line and cooperates with the guiding member 8 in the folding of the edge portion of the fabric 55 underneath to produce a hem which is to be stitched. The plate 12^b is secured to the body member 12^a by screws 21, 21 passing through a slot 22 in the body portion and threaded into the plate. The purpose of these screws 60 is to permit the plate to be shifted on the

body portion of the fabric supporting member. After the plate 14 is properly set for guiding the edge of the fabric section, the plate 12^b is shifted so as to properly position the same to cooperate with the fabric guiding member 8 in the forming of the hem. In other words, the hem forming portion of the fabric supporting and guiding member and the edge guiding portion thereof are independently shiftable to different set positions. The body member 12^b is also provided with a depending lug 23 which serves as a stop to limit the inward swinging motion of the fabric guiding and supporting member 12. This stop engages the side face of the plate 14. It serves to limit the inward swinging movement of the plate due to the passing of the fabric sections thereover and holds the plate normally in a set operative position. The operator may quickly swing the plate to the position shown in the broken lines in Fig. 1. No latches are required to hold the plate. The portion 24 of the plate 12 through which the pivot screw 13 passes makes contact with a relatively wide portion of the plate 14 beneath the same, and this serves as a frictional means for holding the fabric supporting and guiding plate in its normal set position. The body portion 12^a has the edge 90 portions thereof turned down so as to form a housing for the plate 12^b.

While the guiding means has been described as particularly adapted for forming a hem fold wherein the edge of the fold is covered by the stitching threads, it will be understood that from certain aspects of the invention the inner edge of the folded under section may be again infolded, in which case it would be necessary to use only one line of stitching.

From the above it will be apparent that a fabric guiding means has been provided for turning a hem fold, wherein the fabric guiding member over which the fabric is folded can be withdrawn at will. In the hemming of bath robes which are made of relatively heavy material, the hem extends continuously on both sides of the front and around the bottom. In turning the corners, the fabric turned underneath is greatly increased in thickness and it is difficult to pass it through a folder with the inner member in place. The operator, therefore, swings this inner member out of the folder while turning the corner. Then again, in forming circular hems, it is desirable to remove the inner member from the hem fold in order to complete the stitching of the hem, and this can be readily accomplished on the fabric guiding means above described.

It is obvious that minor changes in the details of construction and the arrangement of the parts may be made without departing from the spirit of the invention as set forth in the appended claims.

Having thus described the invention, what I claim as new and desire to secure by Letters-Patent, is—

1. A fabric guiding means for forming a hem comprising an edge guiding and folding member located at one side of the stitching line, a fabric supporting member extending across the stitching line and cooperating with said edge guiding and folding member for underfolding the edge portion of the fabric section, a supporting plate on which said fabric supporting member is pivotally mounted whereby the same may be swung for withdrawing said fabric supporting plate from the hem fold to permit the completing of the stitching of the hem, said supporting plate serving as an edge guide for the folded under edge of the fabric section, and said fabric supporting member being formed in sections whereby the position of the outer end thereof may be adjusted relative to its pivotal support.

2. A fabric guiding means for forming a hem comprising an edge guiding and folding member located at one side of the stitching line, a fabric supporting member extending across the stitching line and cooperating with said edge guiding and folding member for underfolding the edge portion of the fabric section, a supporting plate on which said fabric supporting member is pivotally mounted whereby the same may be swung for withdrawing said fabric supporting plate from the hem fold to permit the completing of the stitching of the hem, said supporting plate serving as an edge guide for the folded under edge of the fabric section, and said fabric supporting member being formed in sections whereby the position of the outer end thereof may be adjusted relative to its pivotal support, and a lug carried by said fabric supporting member adapted to engage said supporting plate for limiting the movement thereof to normal set position.

3. The combination of a work support and a fabric guiding means for forming a hem including an edge guiding and folding member located at one side of the stitching line, means for adjustably securing said member to the work support so that it may be shifted toward and from the stitching line, a fabric supporting member extending across the stitching line and cooperating with said edge guiding and folding member for underfolding the edge portion of the fabric section, a supporting plate on which said fabric supporting member is pivotally mounted so that it may be swung in a horizontal plane toward and from the edge guiding and folding member, means for adjustably supporting said plate on the work supporting plate whereby it may be shifted in a direction toward and from the line of stitching and the edge of the supporting plate set for guiding the edge of the underfolded portion of the fabric section.

4. The combination of a work support and a fabric guiding means for forming a hem including an edge guiding and folding member located at one side of the stitching line, means for adjustably securing said member to the work support so that it may be shifted toward and from the stitching line, a fabric supporting member extending across the stitching line and cooperating with said edge guiding and folding member for underfolding the edge portion of the fabric section, a supporting plate on which said fabric supporting member is pivotally mounted so that it may be swung in a horizontal plane toward and from the edge guiding and folding member, means for adjustably supporting said plate on the work supporting plate whereby it may be shifted in a direction toward and from the line of stitching and the edge of the supporting plate set for guiding the edge of the underfolded portion of the fabric section, and a lug carried by said fabric supporting member adapted to engage said supporting plate for limiting the swinging movement of the fabric supporting member toward the edge guiding and supporting member.

5. The combination of a work support and a fabric guiding means for forming a hem including an edge guiding and folding member located at one side of the stitching line, means for adjustably securing said member to the work support so that it may be shifted toward and from the stitching line, a fabric supporting member extending across the stitching line and cooperating with said edge guiding and folding member for underfolding the edge portion of the fabric section, a supporting plate on which said fabric supporting member is pivotally mounted so that it may be swung in a horizontal plane toward and from the edge guiding and folding member, means for adjustably supporting said plate on the work supporting plate whereby it may be shifted in a direction toward and from the line of stitching and the edge of the supporting plate set for guiding the edge of the underfolded portion of the fabric section, said fabric supporting member including a body portion which is pivoted to the supporting plate, and a fabric plate which is adjustably attached to the body portion and shiftable to different set positions relative to the edge guiding and folding member.

6. The combination of a work support and fabric guiding means for forming a hem including an edge guiding and folding member located at one side of the stitching line, means for adjustably securing said member to the work support so that it may be shifted toward and from the stitching line, a fabric supporting member extending across the stitching line and cooperating with said edge guiding and folding member, for underfolding the edge portion of the fabric section, a supporting plate on which said fabric sup-

porting member is pivotally mounted so that it may be swung in a horizontal plane toward and from the edge guiding and folding member, means for adjustably supporting said plate on the work supporting plate whereby it may be shifted in a direction toward and from the line of stitching and the edge of the supporting plate set for guiding the edge of the underfolded portion of the fabric section, said fabric supporting member including a body portion which is pivoted to the supporting plate, a fabric plate which is adjustably attached to the body portion and shiftable to different set positions relative to the edge guiding and folding member, and a lug carried by the body portion of the fabric supporting member adapted to engage said supporting plate for limiting the movement of the fabric supporting plate toward the edge guiding and folding member.

In testimony whereof, I affix my signature.
